UNITED STATES PATENT OFFICE.

CLEMENT S. CLARKE, OF SHREVEPORT, LOUISIANA.

PIPE TONGS.

Application filed October 28, 1922. Serial No. 597,553.

To all whom it may concern:

Be it known that I, CLEMENT S. CLARKE, a citizen of the United States, residing at Shreveport, in the parish of Caddo and 5 State of Louisiana, have invented certain new and useful Improvements in Pipe Tongs, of which the following is a specification.

This invention relates to improvements 10 in pipe wrenches or tongs.

The primary object of this invention is the provision of pipe tongs embodying a compact arrangement of article engaging jaws, which may be adjusted and relatively 15 moved in facile manner to accomplish the clamping of articles of various sizes, without the necessity of prolonged adjustment and detachable connection of parts.

A further object of this invention is the 20 provision of an improved pipe wrench which may be easily and quickly adjusted for receiving pipes of a wide range of sizes; being capable of operation upon a piece of pipe in such manner as to securely clamp 25 the same in peripheral manner, without the necessity of crushing strains such as is incident to the ordinary pipe tongs or wrenches.

A further object of this invention is the 30 provision of pipe tongs embodying an expandable frame, which is adapted for rotatably receiving a plurality of jaw elements having various sized article engaging surfaces thereon, whereby an article, such as a 35 pipe, may be quickly, conveniently, and effectively clamped.

Other objects and advantages of this invention will be apparent during the course 40 of the following detailed description.

In the accompanying drawings, forming a part of this specification, wherein similar reference characters designate corresponding parts throughout the several views.

Figure 1 is a plan view of the improved 45 pipe tongs, showing the jaw elements thereof adjusted for the reception of a relatively small sized article, such as a pipe.

Figure 2 is a plan view, partly in section, 50 showing the jaw elements of the improved pipe tongs rearranged in order to accommodate a relatively large diameter article, such as a pipe.

Figure 3 is a rear edge view of the improved 55 pipe tongs, showing the various details thereof.

Figure 4 is a side elevation of the improved pipe tongs.

Figures 5 and 6 are perspective views of several types of link members embodied in the frame of the improved wrench. 60

In the drawings, wherein for the purpose of illustration is shown but the preferred embodiment of this invention, the letter A generally designates the improved pipe wrench or tongs, which may include a frame 65 B; jaws or dogs C; and frame adjusting means D.

Referring to the frame construction B, the same is formed as an expandible and contractable loop and may include any number 70 of link members. For ordinary sized pipes, it is preferred that but three link members be used in connection with the frame adjusting means D. These links are preferably 75 the rear link 10, and side links 11 and 12 of similar formation pivotally connected at the ends of the link 10. The link 10 is preferably concavo-convex in formation including the side bars or rail portions 15 and 16, which are of concavo-convex formation, 80 and intermediate their ends provided with aligning apertures 17. Just inwardly of the ends of the bars 15 and 16, they are rigidly connected, as by means of connecting 85 ribs or reinforcing bars 20, which provide the pocket or space 21 intermediate said side bars 15 and 16 and the end bars 20, adapted for rotatably receiving a jaw element C. The ends 23 of the side portions 15 and 16, which extend outwardly from the connecting 90 portions 20 are transversely apertured, as at 24, so that said apertures 24, at the ends of the links 10 are in aligning relation, for receiving the shank portions of bolts 25, which are utilized in connection with the 95 oscillative connection of the links 11 and 12 to the link 10.

The links 11 and 12 are substantially 100 similar in construction, with the exception that link 11 is relatively longer than link 12, in order that it may cooperate with the frame adjusting means D. These side links 11 and 12 each include the irregular shaped side rails or bars 27 and 28, which are transversely apertured as at 29 intermediate their 105 ends, said apertures 29 being in aligning relation. The bar portions 27 and 28 are connected at an end of each by the integral portion 30, which provides a bar or cylindrical shaped lug 31 extending outwardly 110

at the end of said link, and which is provided with a transverse aperture 32. The other ends of the bar portions 27 and 28 are connected as by means of the transverse reinforcing rib 35, which may be V-shaped in cross section, so that the end portions 36 of said bars 27 and 28 extend outwardly of this connection portion 35 and are transversely apertured, as at 37. The transversely reduced and apertured bar portions 31 of the links 11 and 12 are adapted for fitting within the recesses at the ends of the link 10, so that the apertures 24 of the link 10 are in aligning relation with the apertures 32 of the links 11 and 12, for the reception of the bolts 25, and whereby the links of the frame B may be oscillatively connected. The bolts 25 are of detachable construction, including heads 40, and detachable nuts 41. The pockets or spaces 43 intermediate the bars 27 and 28 and the end portions 30 and 35 of each of the side links 11 and 12, are adapted for rotatably receiving jaw elements C, as will be subsequently described in detail. It is to be noted that the ends of the links 11 and 12, which are disposed for cooperation with the frame adjusting means D, are obliquely and relatively inturned.

Referring to the frame adjusting means D, the same principally comprises an operating lever 50, which is oscillatively connected, as by bolts 51 and 52, at an end thereof to the outwardly extending ends 36 of the links 11 and 12 respectively. When the lever 50 is thus connected to the ends of the links 11 and 12, it can be understood that the frame B is loop-shaped, the opening 53 of which may be enlarged or restricted according to the oscillative movement of the lever 50. Upon constricted adjustment of the frame B, the end of the link 12 adjacent the frame adjusting means, is relatively moved toward the concaved side of the adjacent end of the link 11, and upon expansion of the frame opening 53, the ends of the links 11 and 12, which are pivotally connected to the adjusting lever 50, will be moved away from each other incident to their spaced pivotal connection with said lever 50, as can be readily understood.

The jaws or dogs C are adapted for rotatable mounting within the pockets of the links 10, 11 and 12, as upon bolts 55, which are transversely connected to said links, as through the intermediate apertures 17 and 29 provided therein. Each of the jaws C is preferably provided with the flat and parallel surfaces 56 and 57 which may be in sliding engagement with the inside surfaces of the side bars of the links 10, 11 and 12. Each of the jaw members C is furthermore provided with transverse concavities or depressions which are formed by transversely milling or otherwise forming the

arcuate surfaces 60, 61, 62, 63, 64, and 65 thereon, which are struck from different radii, preferably an increasing radii, so that the smaller arcuate surface 60 is struck from a relatively small radius, and is most remotely positioned with respect to the pivot bolt 55, in contra-distinction to the succeeding arcuate surfaces 61, 62, 63, 64, and 65, all of which are struck in the sides of a jaw member C, with proportionately increased radii, and which are in succession more proximately disposed with respect to the pivot opening of the jaw in which the bolt 55 is disposed.

Referring to the operation of the improved type of tongs for the reception of the smallest size of pipe, the jaws C are adjusted in the links of the frame B, so that the smaller arcuate depressions or surfaces 60 are disposed inwardly of the loop opening 53 in facing relation. Upon swinging of the lever D for contraction of the frame opening 53, it is obvious that the jaws C will engage the pipe which is axially disposed through the frame opening 53, so that the arcuate surfaces 60 of the jaws C will peripherally engage the small sized pipe, and securely clamp the same without that crushing action which is incident to the ordinary pipe wrenches, such as the adjustable and detachable link type. The arcuate surfaces 60 to 65 inclusive, of each of the jaws C, may be serrated or toothed in any approved manner, whereby better grip may be had when clamping an article, such as a pipe. For the reception of larger diameter articles, such as pipes, it is merely necessary to oscillate or rotate the member C in the frame links 10, 11 and 12, so that in order to accommodate the largest diameter pipe for which the pipe A is provided, the large depressions in the jaws C which are defined by the arcuate surfaces 65 are placed in the opening 53 of the frame B, as is illustrated in Figure 2 of the drawings, and upon swinging of the operating lever 50, the surfaces 65 will conform themselves to the circumference of the article or pipe to be gripped.

From the foregoing description of this invention, it can be seen that tongs have been provided, by means of which pipes of wide range of diameters may be quickly and conveniently clamped, merely by oscillative or rotative swinging of the jaws C to present the arcuations thereof which more nearly conforms to the circumference of the pipe to be clamped, and the pipe may be effectively clamped merely by contraction of the frame B, as hereinbefore noted. This adjustment is quickly effected, in contra-distinction to the detachable and prolonged adjustable operations which are necessary for the ordinary chain and adjustable types of wrenches now in common use.

Various changes in the shape, size and arrangement of parts, such as the provision of various types of expandible and contraction frames, may be made to the form of invention herein shown and described, without departing from the spirit of the invention, or the scope of the claims.

I claim:

1. In a device of the class described, the combination of a frame comprising a plurality of links pivotally connected to each other, operating means pivotally connected to certain of said links for holding the links in loop forming relation to each other and permitting expansion and contraction of the loop formed by the links when the operating means is moved, and article engaging jaws pivotally carried by said links each including article engaging surfaces located at different distances thereon from the pivotal point of said jaws, whereby different sized articles may be accommodated intermediate said article engaging jaws.
2. In a device of the class described, the

combination of a loop shaped adjusting frame formed of a plurality of link members, means for contraction or expansion of said loop, and a plurality of jaw members rotatably carried by the links of said frame, each of said members including a plurality of transverse arcuations struck from different radii, the surfaces defining said radii being located at different distances with respect to the axis of said jaws.

3. In a device of the class described, the combination of a frame including links pivotally connected in loop shaped formation for relative adjustment, said links having transverse openings or pockets therein in facing relation with the loop of said frame, jaw elements having the sides thereof provided with a series of arcuate depressions therein of different sizes, and means rotatably mounting said jaws within the pockets of said links so that the depressions of said jaws may be selectively disposed in facing relation within the loop of said frame.

CLEM S. CLARKE.
